UNITED STATES PATENT OFFICE

150,576

DESIGN FOR A PUSH-BUTTON SWITCH
OR SIMILAR ARTICLE

Ludwig J. Kalwo, New York, N. Y., assignor to
Trine Manufacturing Corporation, New York,
N. Y., a corporation

Application July 31, 1947, Serial No. 140,646

Term of patent 14 years

(Cl. D26—13)

To all whom it may concern:

Be it known that I, Ludwig J. Kalwo, a citizen of the United States of America, residing at the city, county, and State of New York, have invented a new, original, and ornamental Design for a Push-Button Switch or Similar Article, of which the following is a specification, reference being had to the accompanying drawing, forming a part thereof.

Fig. 1 is a perspective view of a push-button switch showing my new design;

Fig. 2 is a front elevational view thereof;

Fig. 3 is a side elevational view thereof; and

Fig. 4 is an end view thereof.

I claim:

The ornamental design for a push-button switch or similar article, as shown.

LUDWIG J. KALWO.
